UNITED STATES PATENT OFFICE

WINOLD REISS, OF NEW YORK, N. Y.

DESIGN FOR A PILE FABRIC

Application filed July 30, 1929. Serial No. 32,246. Term of patent 3½ years.

To all whom it may concern:

Be it known that I, WINOLD REISS, a citizen of the German Republic, and resident of New York city, in the county of New York and State of New York, have invented a new, original, and ornamental Design for a Pile Fabric, of which the following is a specification, reference being had to the accompanying drawing, forming part thereof.

My new design for a pile fabric is shown in plan view in Fig. 1 of the accompanying drawing, Fig. 2 representing an edge view of the same.

I claim:

The ornamental design for a pile fabric substantially as shown.

WINOLD REISS.
